TRAFFIC SIGNAL SYSTEM

Adelard F. Martel, Burlingame, Calif., assignor of
one-half to George W. Gates, Burlingame,
Calif.

Application April 20, 1936, Serial No. 75,357

1 Claim. (Cl. 177—337)

This invention relates to improvements in traffic signal systems and more particularly to combined control and timer apparatus for signal systems put into operation by a traffic trip switch buried in the traffic lane. The present signal system is particularly useful for intersections of main highways and less travelled lateral cross roads.

Among the objects of the invention is to provide simple and reliable control means for operating the traffic signals to clear the right of way for a predetermined period when a vehicle depresses the trip switch buried in the crossroad traffic lane.

Another object is to enable an uninterrupted flow of traffic along the highway except when a vehicle approaches the intersection from the crossroad.

Another object is to provide for alternate timed "stop" and "go" signals on the highway when a succession of vehicles are travelling on the crossroad.

Another object is to conserve the consumption of current at night when the traffic is light while still providing for adequate traffic signalling.

Other objects and advantages appear as the description progresses.

In this specification and the accompanying drawings the invention is disclosed in its preferred form. However, it is to be understood that it is not limited to this form because it may be embodied in other forms within the purview of the claims following the description.

In the two sheets of drawings:

Fig. 1 is a side elevation of the control box showing the control and timer unit.

Fig. 2 is a schematic diagram of the electrical circuits included in the system.

In detail the construction illustrated in the drawings, referring more particularly to Fig. 2 comprises the tripper 1 buried in the pavement of the lateral road and is operable by the wheels of vehicles passing thereover. It is of the general type illustrated and described in detail in my Patent #1,962,451 entitled "Traffic signal controls". The tripper is adapted to close the switch 2 which is interposed in an electrical circuit consisting of the source of electromotive force 3, the conductors 4 and 5, the solenoid 6, and the conductors 7, 8, and 9 leading back to the current source 3.

The lever 10 is pivoted at 11 on the base 12 within the control box 13. The ferrous core 14 engages the lever 10 and extends into the solenoid 6. The solenoid 6 is mounted on the bracket

15 fixed on the standard 16 extending upward from the base 12.

The lever 10 has the non-conducting block 17 thereon with the bus-bars 18 and 19 fixed therein. The contacts 20—20 and 21—21 are mounted on the insulating panel 22 on the bracket 15 and are adapted to be engaged by the bus-bars 18 and 19 when the solenoid 6 is energized. The contacts 21—21 complete the circuit of the motor 23 which includes the conductors 9, 8, and 24 leading from the current source 3 to the contacts, the conductor 25 connecting the contacts 21 to the motor, and the conductor 26 which leads back to the current source.

The motor 23 is mounted on the support 27 on the base 12 and has the driving worm 28 which engages the worm gear 29 on the shaft 30. The shaft 30 is mounted on the standard 31 integral with the base 12. The disk 32 is rotatably mounted on the fixed shaft 33 and is driven at predetermined speed by the worm gear 28 through the gears 34 and 35.

The switch lever 36 is pivoted at 37 on the standard 31 and is normally maintained in the inoperative position by the roller 38 on the disk 32. The spring 39 urges the lever 36 toward the operative position. The con-conducting arm 40 is pivoted on the lever 36 at 41 and has the bus-bar 42 set therein opposite the contacts 43—43. These contacts are mounted on the insulating block 44 fixed on the bracket extension 45 on the standard 16.

The movement of the lever 36 is transmitted to the arm 40 by the pin 46 operating in the arcuate slot 47. The spring 48 resiliently engages one end of the slot 47 against the pin 46. The assembly operates to produce a snap switch action to avoid arcing when the bus-bar 42 is disengaged from the contacts 43. When the lever 36 is operated to disengage the bus-bar from the contacts, the friction between these spring contacts 43 and the bus-bar causes the bus-bar to remain in engagement with the contacts against the tension of the spring 48 which urges it therefrom. As the movement of the lever 36 progresses, the pin 46 arrives at the end of the arcuate slot 47. The continued movement of the lever 36 then forces the bus-bar 42 outward from the contacts 43. When the bus-bar 42 is once released from the contacts, the spring 48 snaps it away therefrom in the manner of the usual snap switch.

The contacts 43—43 are connected in parallel with the contacts 21—21 and serve as an auxiliary motor switch in the operation of the system as later described.

The upper end 49 of the lever 10 extends upward into juxtaposition to the disk 32. The pin 50 fixed on the disk is arranged to restore the lever 10 to inoperative position, disengaging the bus-bars 18 and 19 from the contacts 20 and 21. The upper end 49 of the lever 10 is arranged to clear the revolving roller 38.

The substantially semicircular lever 51 surrounds the disk 32 and is pivoted at 52 on the standard 53 extending upward from the motor base 27.

The lever 51 has the cam 54 which is adapted to be engaged by the revolving roller 38 to swing the lever 51 into its secondary position. The cam 55 is similarly adapted to cooperate with the roller 38 to restore the lever 51 to its original position. The cam 55 is secured to the lever 51 by the screw 56. Interspaced screw holes 57 are provided in the lever 51 so that the position of the cam 55 can be moved to adjust the timing of the two phases of the signal operation.

The non-conducting arms 58 and 59 are pivoted on the ends of the lever 51 at 60 and 61. The pin and slot connections 62 and 63 and the springs 64 and 65 provide a resilient cooperation between the lever 51 and the arms 58 and 59 similar to that previously set forth in describing the snap action of the arm 40 on the lever 36.

The bus-bars 66 and 67 set in the arm 58 cooperate with the contacts 68-68 and 69-69 on the insulating block 70. This block is fixed on the lug 31' extending laterally from the standard 31. The switch contacts 68-68 are interposed in the circuit of the solenoid 6 between the conductors 7 and 8.

The conventional signals H-H are placed at the side of the main highway near the intersection. The signals C-C are similarly mounted on the cross road. The signals are provided with the usual green, amber, and red lamps or other conventional indicia for regulating traffic.

The green lamps 71, 72 in the highway signals and the red lamps 73, 74 in the cross road signals are in an electrical circuit including the current source 3, the conductors 9 and 8, the switch contacts 69-69, the conductor 76 leading to the lamps and the conductor 77 leading back to the source 3.

The amber lamps 78, 79, 80, 81 of all of the signals are in a circuit controlled by the switch contacts 20-20 previously described. The contacts are connected to the current source 3 by the conductors 9, 8 and to the amber lamps 78 to 81 by the conductor 82. The conductor 77 completes the circuit from the lamps back to the source 3. The warning signal lamps 84, 85 are connected in parallel with the lamps 78 and 81 in a mesh consisting of the conductors 86, 87, 88. These lamps are placed some distance along the highway from the intersection to forewarn the approaching motorists. The thermal flasher switch 89 may be interposed in the circuit of the lamps 84, 85 to increase their effectiveness.

The circuit including the red lamps 90, 91 on the highway and the green lamps 92, 93 on the crossroad is controlled by the switch contacts 94-94. The non-conducting arm 59 has the bus-bar 95 thereon for cooperation with the contacts 94-94. The contacts 94 are connected to the current source 3 by the conductors 9, 8 and to the signal lamps by the conductor 96. The conductor 77 connects the lamps back to the source 3 to complete the circuit.

The traffic bell 98 is placed at the intersection 75 to direct attention to changes in the visual traf-

fic signals. It is interposed in a circuit controlled by the non-burning contacts 99-99 on the resilient metal strips 100, 101 which are mounted on the insulating block 70. The lever 102 is pivoted on the block 70 and has the roller 103 impinging on the strip 100. The cam 104 on the lever 51 engages the lever 102 and is arranged to swing this lever to close the contacts 99-99. When the lever 51 is swung from one of its operative positions to the other, as later described, the cam 104 operates the lever 102 to close the contacts 99. The time the contacts 99 are closed is brief. Its duration depends upon the time required for the roller 38 to operate the cams 54 and 55 to swing the lever 51 between its two operative positions. The contacts are supplied with current from the source 3 through the conductors 9, 8 and are connected to the traffic bell 98 by the conductor 105. The conductors 106, 77 lead back to the source.

A modified control mechanism is provided for 20 signaling during the hours of light traffic at night. The modified control and timer is similar, except in details, to that above described. The same reference numerals with the addition of the prime character are used to indicate similar parts in 25 the modified structure. The night signal control can be mounted in the same control box 13. In the night control, the contacts 69-69 and the bus-bar 67 are omitted. This maintains the green lamps 71, 72 on the highway and the red 30 lamps 73, 74 on the crossroad unlighted. The volume of traffic during certain hours does not warrant the expenditure of current to maintain the signals continuously illuminated. The contacts 99-99' controlling the traffic bell 98 can be similarly omitted in residential districts where it is 35 desirable to preserve quiet at night. The disk 32' is driven at a greater speed than the disk 32 so as to provide for a more rapid sequence of signals than is possible with the more congested traffic in 40 daytime.

The time switch 107 selectively governs the operation of the day and night control mechanisms. The switch 107 either connects the conductor 9 to the conductor 8 which feeds all of the switch contacts in the day control or it connects the conductor 9 to the conductor 8' which is similarly in circuit with the night control. The times of the operation of the switch can be regulated by the manual knob 108 (see Fig. 1).

The manual switch 109 is wired in parallel with the time switch 107 and enables an officer to continue the operation of the day control at night when necessary. The switch 110 is provided to cut out the time switch 107 when the manual 55 switch is being used.

The signal system operates substantially as follows: Assuming the time switch 107 is in position to render the day control and timer operative, the parts thereof occupy inactive positions 60 as shown in Figs. 1 and 2. The contacts 68-68 and 69-69 are normally closed by the bus-bars 66 and 67. The switch contacts 69-69 thus close the circuit, previously traced, of the green lamps 71, 72 in the highway signals and the red lamps 73, 74 in the crossroad signals. These lamps remain illuminated except when a vehicle approaches from the crossroad thus maintaining the main highway unobstructed as long as no vehicle enters the intersection from the crossroad. 70

The driver of a vehicle approaching the intersection from the crossroad is directed by suitable road signs to drive over the tripper 1. This closes the switch 2 and energizes the solenoid 6 through the conductors 4, 5 and 7 and the switch 75

contacts 68—68. The core 14 attracted into the solenoid swings the lever 10 and closes the contacts 20—20 and 21—21. The core 14 remains in this operative position even after the solenoid 5 is deenergized by the automatic opening of the switch 2 after the vehicle has passed over the tripper 1. The switch contacts 20—20 complete the previously traced circuit of the amber lamps 78, 79, 80, 81 and the flashing signal lamps 84, 10 85 thus warning the oncoming traffic of the impending change of signals.

The switch contacts 21—21 complete the circuit also previously traced of the motor 23. The motor then drives the disk 32 at the predetermined constant speed. The revolution of the roller 38 on the disk 32 carries it beyond the end of the switch lever 36. The spring 39 then swings the lever 36 downward to engage the bus-bar 42 in the contacts 43—43. These closed contacts 20 maintain the motor circuit closed after the contacts 21—21 have been opened by the restoration of the lever 10.

The continued revolution of the roller 38 after a predetermined interval carries it into engagement with the cam 54 and swings the lever 51 on its pivot 52. This engages the bus-bar 95 in the contacts 94—94. This closes the circuit previously described and illuminates the red lamps 90, 91 in the highway signal and the green lamps 30 92, 93 in the crossroad signal.

The bus-bars 66 and 67 simultaneously snap out of engagement with the contacts 68—68 and 69—69. The breaking of the contacts 69 opens the circuit of the green lamps 71, 72 on the arterial and the red lamps 73, 74 on the lateral. The opening of the contacts 68—68 opens the circuit of the tripper switch 2 and the solenoid 6. This enables the vehicles on the crossroad to pass over the tripper when the green light is showing 40 without energizing the solenoid 6.

The movement of the lever 51 produced by the roller 38 causes the cam 104 to swing the roller 103 on the lever 102 against the resilient strip 100 to close the contacts 99—99. This rings the traffic bell 98 through the circuit previously traced at the time the signals are changing.

While the lever 51 is being moved by the roller 38 the pin 50 engages the upper end 49 of the lever 10 and restores it to the inactive position shown in Fig. 1. This opens the contacts 20—20, 21—21. The opening of the contacts 20—20 breaks the circuit previously described of the amber lamps 78 to 81 and the warning signal lamps 84, 85. The contacts 21—21 are interposed 55 in the circuit of the motor 23 as previously described. However, the operation of the motor is continued due to the closed switch contacts 43—43 which are wired in parallel with the contacts 21—21.

After a predetermined time interval, the roller 38 revolves into engagement with the cam 55 and restores the lever 51 to its original position. This opens the contacts 94—94 and opens the circuit of the red lamps 90, 91 on the arterial and the green lamps on the lateral. The closing of the contacts 69—69 illuminates the green lamps 71, 72 on the highway and the red lamps 73, 74 on the crossroad. Closing the contacts 68 again

completes the circuit of the solenoid 6 so that the next vehicle passing over the tripper 1 will energize the solenoid.

After the roller has continued to revolve for another predetermined interval, it comes into operative engagement with the lever 36. The lever is thus swung on its pivot 37 and snaps the bus-bar 42 out of engagement with the contacts 43—43. If the tripper has not been operated by a vehicle in the lateral passing there-over, the opening of the contacts 43—43 halts the motor 23 leaving the control unit in readiness for another cycle of operation initiated by a vehicle passing over the timer.

If the tripper has been operated during the latter phase of the operation of the control and timer, the energization of the solenoid 6 closes the contacts 21—21. The operation of the lever 36 by the roller 38 disengaging the bus-bar 42 from the contacts 43—43 thus will not halt the operation of the motor because of the closed contacts 21—21. The control unit then, without pausing, will pass through another cycle of operation.

At a predetermined time, the time switch 107 reverses itself opening the circuits through the wire 9 and closing the circuits fed by the wire 8'. This places the night control unit into operation. The operation of this control is substantially similar to that above described. It is desirable to drive the disk 32' at a greater speed than the disk 32 to permit more rapid control of a lighter volume of traffic. The contacts 64—64 being omitted, the green lamps 71, 72 on the highway and the red lamps 73, 74 on the crossroad are not illuminated.

Having thus described this invention, what is claimed and desired to be secured by Letters Patent is:

In a traffic signalling system, a motor circuit including an electric motor, and two switches in parallel for energizing said motor when either is closed, a disc driven by said motor, lugs on said disc spaced in the direction of rotation of the disc, means operated by one lug to open one of said switches when engaged by the lug, a lever in the path of the second of said lugs and movable to switch opening and switch closing position for operating the second of said switches, means operated by traffic for moving said lever to switch closing position whereby the motor is energized and the disc rotated and the first lug moved away from said one switch opening position, means to thereupon close said one switch, the second lug thereafter moving said lever to open the second switch, an arcuate control element having a cam thereon in the path of the first lug to shift the position of said control element upon engagement by said first lug, a second cam circumferentially adjustable on said control element, and adapted to restore said control element to its original position upon engagement by said first lug, traffic signals, and means to display one group of signals when the control element is in one position, and a second group when the control element is in the original position.

ADELARD F. MARTEL.
